FLUE LINER

James J. Dyer, Toronto, Ohio

Application January 8, 1940, Serial No. 312,895

5 Claims. (Cl. 72—94)

This invention relates to a flue liner and more particularly to flue liner elements made of vitrified ceramic material which may be assembled end to end to form a flue liner which prevents the flame, combustion gases or soot passing through the flue from leaking through the joints, even though the joints may not be entirely tight.

In the accompanying drawing, which illustrates the preferred embodiment of my invention—

Fig. 1 is a vertical section of a portion of a flue formed of liner elements according to the present invention, and also a portion of the surrounding brickwork.

Fig. 2 is a plan view of one of the liner elements, and

Fig. 3 is a perspective view of the top portion of one of the liner elements.

Flue liners have generally been made in the past by assembling a series of liner elements one on top of the other with mortar or other cementing medium in the joints, the liner elements having flat substantially horizontal top and bottom surfaces. The joint between the top of one liner element and the bottom of the next higher element is exposed to the flame and gases within the flue. If the joints are not tight, the draft may be cut down because of infiltration of cold air. Under certain atmospheric conditions, there is a tendency for the flame, gases or soot to leak through the joints into contact with the surrounding brickwork, and if the brickwork is not tight, this leakage may cause damage to the building.

These disadvantages are overcome by constructing the flue liner elements in accordance with the present invention. I provide a unitary collar on the upper end of the body portion of each liner element, which collar extends above the body portion and is offset inwardly of the inner surface of the wall of the body portion, so as to provide a supporting surface on the upper end of the body portion for the lower end of the next higher liner element. The collar acts as a baffle or shield which prevents direct impingement of the flame, gases or soot passing upwardly through the flue on the joint.

Referring more particularly to the accompanying drawing, the flue liner indicated generally by the reference numeral 2 is made up of a series of flue liner elements 3. The flue is surrounded by brickwork 4 and is spaced slightly from the flue liner as indicated by the reference numeral 5. Each liner element has a body portion 6 formed of front and back walls 7 and

side walls 8. In the embodiment shown, the liner element is square in cross section, the walls 7 and 8 being of equal length. The liner may, however, be of other than square section, being longer in one direction than in the other, or may be circular or of any other desired cross section.

A collar or flange 9 is formed integrally with the body portion 6 and extends upwardly beyond the top surface 10 of the body portion.

10 The collar is offset inwardly of the walls 7 and 8 of the body portion. That is, the area bounded by the collar is less than the area bounded by the body portion 6 of the liner element. The thickness of the collar 9 is preferably less than the thickness of the walls of the body portion. The collar is offset inwardly of the walls of the body portion a sufficient distance, so that the top surface 10 will form a supporting surface for the bottom surface of the next higher liner element 20 and the liner elements when assembled will have their outer surfaces 11 in alignment with each other. The joints between the liner sections are filled with mortar 12 or other cementing material. The top surface 10 is provided with a groove 13 which anchors the mortar used in the joints. This groove may be semi-circular as shown, or 25 of any other desired shape.

The flame and gases traveling upwardly in the flue are prevented from impinging directly on the joints between the liner elements because of the collar 9 on each element. The collars act as baffles which direct the flames past the joints. The collars will prevent escape of flame, gases and soot from the flue, even though the joints 30 between the elements are not completely tight. The collars prevent the mortar from being squeezed out of the joints into the interior of the flue while the mortar is hardening, thereby preventing clogging of the bottom of the flue, or forming projections on the inside of the flue which would collect soot. The surface of the collar is smooth and does not collect soot as readily as would a rough mortar surface. The surfaces 10 are sloped downwardly and outwardly, so that in the event that any condensation occurs within the flue, it will filter through the joint material and escape along the sloping surface 10 to the outside of the flue.

45 The flue liner elements may be made by an extrusion process similar to that disclosed in my Patent No. 1,978,420, granted October 30, 1934, or by other suitable process. This avoids the expense incident to, and the weakening of the liner element which would result from cutting away a portion of the wall of the element, in

order to provide a collar and a supporting surface for the adjacent liner element.

Although it is preferred to make the liner elements of vitrified ceramic material such as vitrified clay or shale, they may be made of other suitable material. I may use concrete, asbestos or a mixture of concrete and asbestos.

Although I have illustrated and described the present preferred embodiment of my invention, it is to be understood that the invention may be otherwise embodied or practiced within the scope of the following claims.

I claim:

1. A flue liner element comprising a body portion enclosing a flue passage, a unitary collar formed on the upper end of the body portion and extending above and coextensive with the body portion, the collar being offset inwardly of the inside wall of the body portion, so as to provide a supporting surface on the upper end of the body portion for the lower end of an adjacent liner element.

2. A flue liner element made of vitrified ceramic material and comprising a body portion enclosing a flue passage, a unitary collar coextensive with and corresponding in the shape of its cross section to the cross section of the body portion and formed on the upper end of the body portion and extending above the body portion, the collar being offset inwardly of the inside wall of the body portion so as to provide a supporting surface on the upper end of the body portion for supporting the lower end of an adjacent liner element.

3. A flue liner element made of vitrified ceramic material and comprising a body portion of rectangular cross section enclosing a flue passage, a unitary collar of rectangular cross section corresponding to the shape of the cross section

of the body portion and formed on the upper end of the body portion and extending above the body portion, the collar being offset inwardly of the inside wall of the body portion, so as to provide a supporting surface on the upper end of the body portion for the lower end of an adjacent liner element.

4. A flue liner element made of vitrified ceramic material and comprising a body portion enclosing a flue passage, a unitary collar formed on the upper end of the body portion and extending above and coextensive with the body portion, the collar being offset inwardly of the inside wall of the body portion, so as to provide a supporting surface on the upper end of the body portion for the lower end of an adjacent liner element, said supporting surface which is located at the upper end of the body portion sloping downwardly toward the outside of the liner element.

5. A flue liner element comprising a body portion enclosing a flue passage, the bottom of said body portion formed of one continuous surface extending the full thickness of the body portion whereby the body portion is not weakened by cut out portions, a unitary collar formed on the upper end of the body portion and extending above and coextensive with the body portion, the collar being offset inwardly of the inside wall of the body portion, so as to provide a supporting surface on the upper end of the body portion for the lower end of an adjacent liner element, said collar extending a sufficient distance above the body portion to act as a baffle which effectively protects the joint between adjacent liner elements from the gases flowing through the flue passage.

JAMES J. DYER.
